(57) **CLAIM**

We claim, the ornamental design for a meniscus repair device, as shown and described.

DESCRIPTION

FIG. 1 is a perspective view of a meniscus repair device showing our new design;

FIG. 2 is a front elevational view of the meniscus repair device of FIG. 1;

FIG. 3 is a rear elevational view of the meniscus repair device of FIG. 1;

FIG. 4 is a left-side view of the meniscus repair device of FIG. 1;

FIG. 5 is a right-side view of the meniscus repair device of FIG. 1;

FIG. 6 is a top plan view of the meniscus repair device of FIG. 1; and,

FIG. 7 is a bottom plan view of the meniscus repair device of FIG. 1.

The broken lines shown in the drawings are included for purposes of illustrating portions of the design or environment and form no part of the claimed design.

1 Claim, 3 Drawing Sheets
